UNITED STATES PATENT OFFICE.

CARL HERMANN STAMER, OF HAMBURG, GERMANY.

WATER-GAGE.

SPECIFICATION forming part of Letters Patent No. 442,465, dated December 9, 1890.

Application filed June 3, 1890. Serial No. 354,151. (No model.) Patented in Germany March 26, 1889, No. 52,472, and in England June 22, 1889, No. 10,220.

To all whom it may concern:

Be it known that I, CARL HERMANN STAMER, a subject of the German Emperor, and a resident of Hamburg, in the German Empire, have 5 invented certain new and useful Improvements in Valves and Water-Gages, (for which I have secured Letters Patent in England, No 10,220, dated June 22, 1889, and in Germany, No. 52,472, dated March 26, 1889,) of 10 which the following is a specification.

My invention relates to improvements in valves and water-gages, and the objects of the same are to provide suitable closing devices for lifting-valves, such as plug-valves, and 15 efficient contrivances for causing in water-gages the steam and water to be instantaneously and automatically shut off when the glass bursts, and allowing the closing of the automatically-acting valves to be with facility 20 obviated while blowing the steam through the glass tube for cleansing purposes. I attain these objects by the mechanism illustrated in the accompanying drawings, in which—

Figure 1 illustrates a vertical section of a 25 water-gage constructed according to my invention, and showing, as an example, my improved closing device adapted for use in any kind of lifting or plug valves. Fig. 2 is a horizontal section on the line II II, and Fig. 3 a 30 horizontal section on the line III III of the upper part of my improved water-gage, Fig. 1 illustrating the arrangement of the steam-passages to permit the communication of the socket connected to the boiler with the gage-glass, while Fig. 4 represents a horizontal section 35 on the line IIII IIII, Fig. 1, of the lower part of my improved water-gage.

Similar letters refer to similar parts throughout the several views.

40 The main part of my invention relates to the novel method by which an enduring tight closing of the valves is insured, and this is performed by the employment of a plug *t* of soft copper or other soft metal, the sharp-edged 45 face of which is adapted to establish a tight closing in the conical seat *a* of the passage of the fluid in the valve-casing. This copper plug tapers toward its free extremity, in order to allow its tight fit in the conical seat *a* to be 50 re-established, when necessary, by renewing

its sharp circular edge. As the conical form of the plug differs from that of its seat in the valve-casing, and as, further, the renewal of the sharp edge of the plug can easily be effected by turning or filing off the hollow 55 face of the conical plug, the renewed circular edge of the latter, on account of its diameter being larger than that of the cut-off worn edge, will consequently meet a new untouched closing-surface in the corresponding seat *a*, 60 and therefore an enduring tight fitting of the plug in its seat is insured. This closing device is particularly applicable for water-gages and gage-cocks of the style illustrated in the drawings. The upper part of the water-gage, 65 Figs. 1 to 3, consists of a casing *g*, having attached to its rear side the socket-piece *k* with flange *k'* or a suitable screw-plug, and to its front, opposite to the socket-piece *k*, the cleaning-aperture, which is closed by the screw- 70 plug *o*. The valve-spindle *s*, adjustable by means of a screw-thread *s'* in the nut *m*, and tightened outwardly through the stuffing-box *p*, is provided so as to traverse the cleaning device at an angle of about thirty degrees. To 75 the internal extremity of the spindle *s* is connected the above-described plug-valve *t* of soft copper or other soft metal, which fits in the conic bore *d* of the passage to the steam-generator. Sidewise of the socket *k* is provided the tube-muffle *r*, and in front of the latter the valve-chamber *v*, communicating through the passage *d* with the casing *g* and through the passage *c* with the tube-muffle *r*, thereby allowing the steam to flow through 85 the upper part of the water-gage to the gage-glass, in the direction indicated by the arrows.

The valve-chamber *v* is provided between the aperture *d* and passage *c* with a partition *v'*, having a bore or opening *a'*, tightly closed 90 by means of the sharp-edged copper plug *t'*, which is guided by aid of its stem in the closing-screw *f*, and adapted to be taken out therewith for cleaning or other purposes.

When the gage-glass bursts, the steam, rushing 95 through the casing *g*, causes the valve *t'* to be instantaneously closed, while, in order to obviate the closing of the valve when the steam blows through the glass-tube for cleaning the same, the screw-spindle *g'*, provided 100

in the upper part of the valve-chamber, is slightly turned, thereby arresting the copper plug t' .

The automatic closing of the lower part of the water-gage, which part is of the same construction with the analogous portion of the upper part, except that the chamber g^3 is in direct communication through the passage d^2 with the respective tube-muffle r' and the valve-chamber v omitted, is effected by means of the copper plug t' , which is adapted to fit in a bore or opening v^2 of a passage in the muffle r' , and is guided either in the bow of a closing-screw f , as the plug t' in the upper part of the water-gage, or in a branch f' of the casing of the lower delivery-valve h . The tight closing of the latter, which being, for sake of clearness, represented as turned for ninety degrees, is likewise insured by means 20 of a copper plug t' , provided on the valve-spindle s' and extending into a conic bore a^3 of the casing.

Having now fully described my invention, what I claim, and desire to secure by Letters Patent, is—

As an improvement in water-gages, the casing having a socket-piece k , a lower passage-way connecting with said socket-piece, an upper passage c , and a diaphragm having a bore or opening, the valve-chamber v , the vertically-disposed valve having a tapering end designed to fit said bore or opening, the screw-spindle g' , designed to engage said valve, and the horizontally-disposed valve fitting a conical seat in the passage from said socket-piece, substantially as set forth.

In testimony that I claim the foregoing as my invention I have signed my name, in presence of two witnesses, this 29th day of April, 1890.

CARL HERMANN STAMER.
